UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR A COOKING-STOVE.

Specification forming part of Design No. 7,009, dated December 2, 1873; application filed September 12, 1873.
[Term of Patent 3½ years.]

To all whom it may concern:

Be it known that we, NICHOLAS S. VEDDER, a resident of Troy, in the county of Rensselaer and State of New York, and TOBIAS S. HEISTER, a resident of Lansingburg, in said county and State, have jointly invented and produced a new and original ornamental Design for Cooking-Stoves, of which the following is a specification, reference being had to the accompanying wood-cut or engraving of a stove which embodies our said new design.

One part of our invention consists of the design for the compound ornament, A, for the oven-door panel, which has its lower part extended forward of its upper portion; the said ornament A being composed of a central oval shield, having thereon rows of ornamented lozenge-shaped figures, surrounded by a beaded border, and disposed upon the face of a projecting ornamented back piece, having an ornamented gable or triangular top, and, at the bottom, a central and two lateral ornamented pendants, with a compound scroll-work ornament extending forward from the front one of the said pendants, and all the parts shaped, ornamented, and arranged together substantially as shown in the aforesaid engraving. Another part of our invention consists of the design for the oven-door, as distinguished by the compound ornament A, composed as above specified, and arranged on the panel of the door, in combination with the compound border-molding B, composed of the outer convex molding, c, inner row of oval beads e, and intervening concave molding, d, all shaped and disposed so as to appear substantially as represented in the accompanying cut. Another part of our invention consists of the design for the end door of the fire-box, as distinguished by the row of oval beads around the plain rectangular panel, having on its middle the compound ornament E, composed of the circular or oval center-piece, having thereon rows of quadrangular forms surrounded by a row of beads, with ornamented roof-like or angular extensions at the top and bottom, and hub-like projections at the sides, and the whole shaped and disposed so as to appear substantially as shown in the afore-

said cut. Another part consists of the design for the front door, G, as composed of the flat oblong panel h, having the straight bottom, parallel upright ends, and curved or arched top, and surrounded by the compound border i, consisting of the inner row of oval beads and the two united outer curved moldings, all shaped and disposed as shown in the aforesaid cut. Another part consists of the design for the upper front plate, as distinguished by the two oblong rectangular projecting panels J J, arranged upright on the end portions of the said front plate, and each having a plain flat tablet, k, surrounded by an ornamental border, l, composed of the inner row of beads and the outer curved molding, all shaped and disposed as shown in the aforesaid engraving. Another part consists of the design for the leg M, as composed of the central oval ornament, having rows of lozenge-shaped figures thereon, surrounded by two rows of bead-like ornaments, and arranged upon the upper or knee portion of the leg, with ornamental forms disposed along and upon the sides and the lower portion of the leg, and all shaped substantially as represented in the aforesaid cut.

What we claim as our joint invention is—

1. The design for the compound ornament A, composed of the several parts herein specified, shaped and arranged together, and upon the panel of a stove-door, substantially as represented in the accompanying engraving.

2. The design for the oven-door, consisting of the compound ornament A, arranged on the plain surface of the panel, in combination with the panel-border B, composed of the row of beads e and moldings c d, substantially as represented in the aforesaid cut.

3. The design for the end door of the fire-box, as distinguished by the row of beads around the rectangular panel, in combination with the compound ornament F, composed and arranged on the panel as herein set forth.

4. The design for the front door G, as composed of the oblong panel h, arched at its top, and surrounded by the border i, formed of the inner row of oval beads and outer moldings, shaped and arranged as described and shown.

5. The design for the upper front plate, as distinguished by the two oblong rectangular

panels J J, arranged upon the end portions of the plate, and each having the plain flat tablet k, surrounded by the border l, composed of the inner row of oval beads and outer molding, as described and shown.

6. The design for the leg M, composed of the central oval ornament, having lozenge-shaped figures surrounded by two rows of beads, between ornamented forms along the sides of the

leg, and extended to the lower part thereof, substantially as represented in the accompanying illustrative engraving.
